UNITED STATES PATENT OFFICE.

RICHARD H. CALKINS, OF EAST BLOOMFIELD, NEW YORK.

JAR-OPENER.

1,366,871.

Specification of Letters Patent. Patented Jan. 25, 1921.

Application filed February 17, 1920. Serial No. 359,263.

To all whom it may concern:

Be it known that I, RICHARD H. CALKINS, a citizen of the United States, residing at East Bloomfield, in the county of Ontario and State of New York, have invented new and useful Improvements in Jar-Openers, of which the following is a specification.

This invention comprehends the provision of a tool to facilitate the opening of jars or the like, the tool being designed to slightly elevate the cover from the rubber gasket at diametrically opposite points, to provide for the admittance of sufficient air to facilitate the removal of the cover.

15 The nature and advantages of the invention will be better understood when the following detail description is taken in connection with the accompanying drawings, the invention residing in the construction, combination, and arrangement of parts as claimed.

20 In the drawings forming part of this specification, like numerals of reference indicate similar parts in the several views and 25 wherein:

Figure 1 is a view in elevation of the tool constructed in accordance with the invention.

Fig. 2 is a view showing the manner of using the tool.

30 The tool forming the subject matter of my invention comprises a pair of crossed handles 10 and 11 respectively which handles are pivoted as at 12, each handle being extended to provide a jaw 13. The jaws terminate 35 to provide inwardly directed lugs or extensions 14, each of which is substantially wedge-shaped in cross section. The jaws are susceptible of movement toward and away from each other to accommodate the 40 tool to jars of different sizes, while the tool itself may be constructed from any suitable material. In practice, the jar to be opened is arranged between the jaws 13, in a manner whereby the lugs or extensions 14 are arranged at diametrically opposite points of 45 the cover A immediately above the rubber

gasket B. A slight pressure upon the handles 10 and 11 to move the jaws toward each other, gently forces the wedges under the cover A to permit of the admittance of 50 air beneath the cover to facilitate its removal.

Each of the jaws 13 is provided at spaced points with lugs 15 which lie in a plane above the extensions 14, the lugs 15 of the respective jaws engaging the cover A at diametrically opposite points to facilitate the 55 removal of the cover after the extensions 14 have been wedged under the lower edge of the cover.

While I have shown and described what I 60 consider the preferred embodiment of the invention, I desire to have it understood that I do not limit myself in this connection and that such changes may be resorted to when desired as fall within the scope of 65 what is claimed.

Having thus described my invention what I claim as new is:-

1. A fruit jar opener comprising a tool including crossed pivoted handles, jaws carried by the handles movable toward and away from each other, there being a substantially wedge-shaped extension constituting the terminal of each jaw, said extensions adapted to be forced between the cover and 70 the gasket therefor to provide for the admittance of air to the cover for the purpose specified.

2. A fruit jar opener comprising a tool including crossed pivotal handles, jaws carried by the handles and movable toward and away from each other, there being substantially wedge shaped extensions constituting the terminals of said jaws and adapted to be forced between the cover and the gasket 75 therefor to provide for the admittance of air to the cover, and lugs carried by the jaws to engage the cover at diametrically opposite points for the purpose specified.

In testimony whereof I affix my signature. 80 85

RICHARD H. CALKINS.
